UNITED STATES PATENT OFFICE.

OPHELIA L. FAY, OF ELYRIA, OHIO.

DESIGN FOR A STOCKING.

SPECIFICATION forming part of Design No. 29,254, dated August 16, 1898.

Application filed July 12, 1898. Serial No. 685,789. Term of patent 14 years.

To all whom it may concern:

Be it known that I, OPHELIA L. FAY, a citizen of the United States, residing at Elyria, in the county of Lorain and State of Ohio, have invented and produced a new and original Design for a Stocking, of which the following is a specification, reference being had to the accompanying drawing, forming a part hereof, which shows a stocking embodying my invention.

The portion *a* of the stocking is of the shape of the human foot, and the stocking tapers in the usual way from the portion *a* to the point *b*, gradually increasing in width from *a* to *b* and being, as usual, tubular. At *c* the back of the tube is open and laid out on opposite sides of the central dividing-line, forming two wings *d d* of equal area on each

side of the longitudinal axis of the tube. At the point *c*, where the edges *e* of the wings join, there is a triangular-shaped piece *x*.

The leading feature of my design is the tubular leg portion divided at the top and formed with two wings of equal area on opposite sides of the longitudinal axis of the tube and the triangular piece at the junction of the wings.

I claim—

The design for a stocking, substantially as herein shown and described.

In testimony whereof I have hereunto subscribed my name.

OPHELIA L. FAY.
